UNITED STATES PATENT OFFICE.

CHARLES J. KLEIN, OF NEW YORK, N. Y., ASSIGNOR TO THE GENERAL INCANDESCENT ARC LIGHT COMPANY, OF NEW YORK.

DESIGN FOR A CUT-OUT CABINET.

SPECIFICATION forming part of Design No. 29,154, dated August 2, 1898.

Application filed June 16, 1898. Serial No. 683,621. Term of patent 3½ years.

To all whom it may concern:

Be it known that I, CHARLES J. KLEIN, a citizen of the United States, residing at New York, in the county of New York and State 5 of New York, have invented and produced a new and original Design for a Cut-Out Cabinet; and I do declare the following to be a full, clear, and exact description of the same, reference being had to the accompanying o drawings, forming a part thereof.

My design consists in the novel article of manufacture shown and described.

Figure 1 is a front view of the cabinet, showing its interior. Fig. 2 is a vertical section 5 taken on the line 2 2 of Fig. 1.

The leading features of my design consist of the strips B B' B² when viewed in connection with the annular overlying holders C.

I claim—

The design for a cut-out cabinet for an 20 electrical distributing system, substantially as herein shown and described.

In testimony whereof I affix my signature in the presence of two witnesses.

CHARLES J. KLEIN.
